ABSTRACT: The present invention is directed to a method for converting a stockpile of material into a moving stream of material for loading into another area. More specifically, the method comprises digging into an angled side face of a pile at its lower end along a continuous path of the length of the side face, creating a first upward arcuate stream of material, creating a second stream of material by digging the angle side face of the pile over an upper area which extends above the lower end, merging the two streams of material into a main stream which is directed angularly from the side face.

METHOD OF RECLAIMING BULK MATERIAL

This is a division of application Ser. No. 504,739, filed Oct. 24, 1965, now abandoned.

The present invention relates generally to a machine here identified as a reclaimer. This machine is adapted to convert a pile of material into a moving stream whereby the material can be loaded into a suitable receptacle such as a truck, railroad car or the like. According to this invention the reclaimer includes as components a sloper for resting on the pile in a plane extending generally transversely of the longitudinal plane of the reclaimer and the path of travel of the reclaimer. As the reclaimer and its sloper move alongside of the pile the sloper cuts into the pile at elevated points to cause material to be dug and released from the pile and flowed as a stream onto a cross conveyor. A circular-type digging wheel is also mounted at one side of the reclaimer and the same conveyor extends transversely through the digging wheel and functions to carry materials dug by the digging wheel in addition to those materials caused to be flowed onto the conveyor by means of the operation of the sloper all in accordance with important features of this invention.

According to other important features of the present invention, the reclaimer employs a three-point suspension with the digging wheel and sloper disposed at one side of the front point of suspension whereby the torque forces can be decreased to balance the digging forces of the digging wheel.

According to still other important features of the present invention, the front point of suspension or crawler has means for steering the reclaimer as well as means for controlling the depth of cut of the digging wheel.

Other important features of this invention relate to the novel method of causing the pile to be dug at a number of spaced points and then causing the dug materials to be joined into a common stream for deposition into a receptacle or truck to be loaded.

According to still more specific features of this invention, the reclaimer employs a novel three-point suspension including three crawlers with the digging wheel disposed forward of the rear pair of crawlers and at one side of the front crawler with the sloper being pivotally mounted on the machine frame and extending in an inclined direction away from one side of the digging wheel with means being provided for raising and lowering the sloper for controlling its elevation.

Other features of this invention are concerned with a novel relationship of elements whereby operating a ram between the reclaimer frame and the front crawler the elevation of the digging wheel as well as the sloper can be regulated.

Another feature of this invention is concerned with the provision of means horizontally aligned and forward of the cross conveyor for digging into the pile and providing a clearance area for positioning of the conveyor enabling a lower end of the sloper to be positioned over the conveyor for direct deposit of sloper cut materials onto the conveyor.

A further feature of this invention relates to the method of reclaiming a pile of material which comprises cycloidally rotating a series of cutters along the slope of the pile into a pile bank creating a stream of downward flowing material, and creating a dam on the rearward side of the cutters confining the downward flow of material between the dam and the pile bank to minimize lateral uncontrolled flow of the cut material.

Still another feature of this invention relates to the provision of plow means on the front crawler for directing portions of the pile into the path of the digging wheel.

Still other features of this invention relate to the position of the plows on opposite sides of the digging wheel for directing pile spillings into the path of the digging wheel.

Another and still further feature of this invention relates to the mounting of a pile cutter on a sloper boom and with the boom having damming means along a face opposite the cutter for confining downward flow of cut material between the damming means and the sloped bank being cut.

In view of the foregoing it will be appreciated that an important object of this invention is to provide a new and improved

machine and method for converting a pile of material into a fast moving controlled stream whereby the stream can be suitably unloaded such as in a receptacle, truck and the like.

A still further important object of this invention is to provide a new and improved machine capable of cutting down a bank of material as well as the sloped face of the material so that the amount of material being dug per running foot of the machine can be maintained at a maximum level.

According to still another feature of this invention, by disposing the wheels or track at the rear of the digging wheel and in front of the digging wheel, a large movement arm is provided so that the reaction forces become very small and the moment in the machine due to the digging forces is resisted.

Other objects and features of this invention will more fully become apparent in view of the following detailed description taken in conjunction with the accompanying drawings illustrating a single embodiment and in which:

20

ON THE DRAWINGS

FIG. 1 is a perspective view of my reclaimer;

FIG. 2 is a fragmentary diagrammatic side view of the reclaimer shown in FIG. 1;

FIG. 3 is a fragmentary front view of the reclaimer;

FIG. 4 is a diagrammatic rear view of the reclaimer shown in FIG. 1;

FIG. 5 is a fragmentary diagrammatic view of the reclaimer shown in FIG. 1;

FIG. 6 is a fragmentary side view of the reclaimer as viewed from the side where the materials are unloaded;

FIG. 7 is an enlarged fragmentary perspective view of the reclaimer illustrating the digging wheel side of the machine where the materials are unloaded;

FIG. 8 is an enlarged fragmentary view of the right rear crawler;

FIG. 9 is an enlarged fragmentary view of the front crawler and its steering mechanism; and

FIG. 10 is a side elevation of the machine illustrating diagrammatically the method of reclaiming the pile.

AS SHOWN ON THE DRAWINGS

The reference numeral 8 indicates generally my reclaimer

45 or reclaimer machine for moving material from a sloped pile 9 to a truck 10. It is significant to note that the machine 8 and the truck 10 are at the same level while the truck is being loaded. The reclaimer differs from conventional trenching machines of the digging wheel-type with this type of machine

50 disposed above the ground level and its digging wheel extends below ground level. The present reclaimer 8 differs thereover in that it is adapted to move transversely of the material to be excavated rather than directly into the material and the digging wheel is disposed generally at the same level as the crawlers or wheels.

GENERAL DESCRIPTION

The reclaimer 8 includes as components a frame 11

60 mounted on a front crawler 12 and inside and outside rear crawlers 13 and 14. As previously mentioned, the machine is provided with a three wheel or three track motivating system and the wheel movement enables precision control of the digging wheel. A wheel receiving area 15 is provided between

65 the front and rear tracks to one side of the front track and a digging wheel 16 is disposed therein and carried by the main frame 11. The digging wheel 16 has a series of buckets 16a for digging into a bank of material.

A cross conveyor 17 extends through the digging wheel 16 and is supported on the frame for receiving dug materials from the digging wheel. A sloper 18 is pivotally mounted on the frame 11 for digging into and freeing materials from the sloped face of the pile. Suitable controls are provided within an operator's cab 19 for operating the various components of 75 the machine including an auger 20 which is positioned im-

mediately forward of the conveyor 17 embodying important features of this invention.

METHOD DESCRIPTION

According to method features of this invention, the sloped pile 9 includes a bank 21 having an angled side face 22 in which the material is reposed at an angle relative to a floor area 23 in immediate adjacency thereto. The method here involved includes the steps of digging into the pile along the side face at a restricted area of the face (comprising the area of the digging wheel) with respect to the total length of the side face and continuing such digging along the length of the side face. The thus dug material is then elevated above the floor in an upward arcuate flow or stream 24 which flow has a horizontal axis at a right angle to the direction of movement of the digging along the side face as best illustrated in FIGS. 4 and 10. A main stream of material 25 is then created from the thus elevated material that flows above the floor area 23 and such stream is directed in angular relation away from the side face 22 and discharged above the floor into the awaiting receptacle or truck 10 (FIG. 4).

According to further important features of my method, a series of cutters 26 are cycloidally rotated causing the angled side face of the pile to be dug over an area which extends a substantial distance above the lower end of the side face along the slope of the pile creating a downward stream of flowing material 27. The downward stream of flowing material is merged with the main stream 25. As the downward flowing stream of material is generated, a dam 28 is created on the rearward side of the cutters along the sloper boom which operates to confine the downward flow of material between the dam and a sloped bank 29 to minimize lateral uncontrolled flow of the cut material.

DETAILED DESCRIPTION

An engine 37 is mounted on the frame 11 for operating the digging wheel 16, the sloper 18 and the auger 20. Coupled with the engine 37 is a transmission or gearbox 38. A drive shaft 39 is in turn connected at one end to the transmission and at an opposite end to an angle box 40 for driving the digging wheel 16 by means of a gear 41a and an internal gear 42. An angled digging wheel driven shaft 40a carries the gears 41 and 41a. The frame structure 11 is also provided with guide or support rollers 43 for supporting the digging wheel on the main frame (FIG. 2).

The rear crawler 14 is mounted on a track pivot arm 44 that is in turn pivotally mounted at 45 (FIG. 3) on the main frame 11. A hydraulic cylinder 46 is connected to an opposite end 47 of the track pivot arm 44 for moving the main frame 11 vertically relative to track frame 14a of the track 14. Suitable controls are provided at the cab 19 for controlling the hydraulic cylinder 45 whereby the digging angle of the digging wheel 16 can be regulated.

The front crawler 12 (FIG. 9) is joined with a frame supporting column 50 for supporting the front end of the frame 11. This column 50 is in turn pivotally secured at 51 and 52 to the main frame 11 by means of the pairs of pivotal parallel column support arms 53 and 54. These arms 53 and 54 are in turn pivotally connected at 54' and 55 to fixed arms 56 and 57 carried on the frame 11. A hydraulic cylinder 58 is pivotally secured at 59 to the main frame between the pairs of arms 53 and 54 and at 60 to the column 50. Suitable controls are provided at the operator's cab 19 for regulating the operation of the hydraulic cylinder 58 to control the digging depth of the digging wheel 16. The column 50 has an upper column arm 65 which carries means 66 (FIGS. 5 and 9) for steering the reclaimer and more particularly the front crawler 12. The means 66 includes a pair of side-by-side hydraulic cylinders 67 and 68. These cylinders are provided with rams 69 and 70 which are connected to steering post connector 71 that is mounted on a steering post 72. The column 50 has a bearing 73 between the column and the steering post 72. The lower

end of the steering post 72 is connected to a crawler yoke 74 which has arms 75 and 76 joined with the track frame 12a.

Mounted on a front end of the front crawler frame 12a is a V-shaped front plow 77 that is so shaped that when the machine is forwardly driven that materials encountered in front of the plow are plowed into the path of the digging wheel. The plow 77 is mounted at opposite sides on pivots 78 and is hydraulically controlled by means of a hydraulic cylinder 79 for raising and lowering the plow. Suitable controls are provided at the cab for controlling the plow. Also, a rear plow 80 is provided on the front crawler frame 12a. The plow 80 is pivotally mounted at 81 on the crawler frame 12a and has a hydraulic cylinder 82 for controlling movement of the plow by means of suitable controls provided at the operator's cab. When the reclaimer machine is driven rearwardly, the plow 80 can be lowered into plowing position, if desired.

It should be further noted that the crawlers or transporting and propelling means are driven by hydraulic motors (not shown) which are in turn coupled with hydrostatic transmissions (not shown) and are operable through suitable controls from the cab. The front crawler is also provided with a front crawler side shield 83 and an upper crawler shield 84 for protecting the crawler from cave-ins and the like during the operation of the machine. It should be noted that the rear shield 84 extends over the track and overhangs a portion of the rear plow 80 to prevent jamming of the tracks.

The auger 20 is mounted transversely of the main frame 11 and transversely of the digging wheel 16. The auger 20 provides means to convey dug material horizontally to the digging wheel 16 which material is dropped into the buckets at the ground level and picked up by the buckets and then transmitted and dumped onto the cross conveyor 17. The auger 20 is disposed in horizontal alignment with the conveyor 17 (FIG. 7) and extends outwardly from one side of the digging wheel 16 as shown in FIG. 5 for the purpose of undercutting the pile being cut so that the conveyor can underlap the pile and permit the materials being dug by the sloper 20 to fall directly onto the conveyor 90 as shown in FIG. 5. By regulating the flow or stream of material falling from the sloped surface of the pile so that such material falls directly onto the conveyor, the digging wheel can then work at full capacity in connection with excavating the material at the side of the pile. According to still further features of this invention, the auger 20 is provided with auger teeth 20a which are angled to one side of the auger blade which assist in the digging into a pile of relatively hard material.

From FIG. 3 it will be seen that the auger 20 has its shaft directly coupled with angled driven digging wheel drive shaft 40a. The auger is carried by an auger bearing 20b that is suspended from the frame (FIG. 7). If desired, a separate hydrostatic transmission can be provided for driving the auger.

A conveyor system 17 is provided for moving the materials dug by the digging wheel 16 from the digging wheel to the truck 10. To this end, a first conveyor 90 is provided which is positioned at one end adjacent to the auger 20 for receiving materials from the sloper 18 and the digging wheel 16. The conveyor 90 is associated with an angled conveyor 91 for delivering materials to an unloading station at its outer end. The conveyor 90 has side plates 92-92 (FIG. 7) cooperable with a first conveyor belt 93 forming a trough to control the material dumped onto the belt 93 from the buckets 16a in the movement of the material to the unloading station at the outer end of the conveyor 91. The conveyors 90 and 91 are driven by hydraulic motors such as shown at 94-94 in FIG. 6. Hydraulic cylinders 95 and 96 (FIG. 6) are positioned between the frame and the conveyor 91 for controlling its elevation. Suitable controls are provided at the cab for regulating the angular position of the conveyor 91.

5
SLOPER

The sloper 18 is mounted at right angles relative to the digging wheel. More particularly, the sloper 18 includes a boom 18a and the forward edge of the boom 18a comprised 5 of the dam indicated at 20 in FIG. 10. The dam consists of series of plates mounted along the vertical extent of the boom 18a for providing a closed area for coacting the sloped bank 29 to provide a method of controlling the downward flow of materials cut by the sloper so that such materials can be readily deposited upon the conveyor 90 with a minimum spillage.

The sloper 18 has the cutters 26 mounted along the length 10 of a cutter drive shaft. The cutters and the device for driving the cutter drive shaft will be the subject of a separate application for patent.

The elevation of the sloper 18 is controlled by a hydraulic 15 cylinder 98 (FIG. 6) that is connected to the frame at its end 99'. The pivot rod of the cylinder 98 is joined to a pulley 99. A cable 100 is joined at one end 101 to the frame 11 and at an opposite end 102 to the sloper boom 18a. Suitable controls are 20 provided at the operator's cab for regulating the operation of the cylinder 90 for pivoting the sloper boom 18a on its boom pivots 18b. The sloper is driven from the engine by a V-belt drive to an angle drive 109 carried on the sloper boom (FIG. 7) to a gearbox 110. It will further be noted that the lower end 25 of the cutter shaft 111 is generally aligned with a leading or forward edge of the conveyor 93 so that as the cutter rotates and as the machine moves forwardly on its crawler tracks, a cycloidal curve will be generated by the cutters 26 to effect cutting of the sloped pile. By operation of the hydraulic cylinder 98, the position of the sloper 18 can be controlled so that the sloper may be lowered to an angle of about 45° or elevated to nearly a vertical position. This angle is determined by the best position for the flow of material onto the conveyor 30 93.

As shown in FIGS. 1 and 3, plows 120 and 121 are positioned at opposite of the digging wheel for the purpose of plowing materials into the path of the digger buckets so that such materials can be lowered onto the conveyor 17. The 40 cone-shaped plow 120 is of a triangular construction and projects upwardly and outwardly from its lower end in such a manner that the upper end of the plow underlies the outer end of the auger 20. The plow 121 extends at an angle relative to the digging wheel 16 so that materials contacting the plow will be caused to be plowed into the bottom area of the digging wheel 16. The cone-shaped plow 120 extends rearwardly beneath the lower back side edge of the conveyor 93 to pick up any materials which may miss being trapped between the 50 side plates 92 to flow such material back into the digging wheel 16 so that interference with the operation of the inside crawler 14 can be minimized.

The present machine has been tested and has been found to be capable of cutting into a pile and converting materials dug into a fast moving stream of material whereby a 12-ton truck 55 can be loaded in the manner of two or three minutes. It has been found that the present machine has a capacity of exceeding the production of two large shovels which have been commonly used for the purpose of loading materials from a pile 60 into a truck.

Although minor modifications might be suggested by those versed in the art, it should be understood that I wish to embody within the scope of the patent warranted hereon, all such modifications as reasonably and properly come within the 65 scope of my contribution to the art.

I claim:

1. A method of reclaiming bulk material from a pile having a side face in which the material is reposed at an angle to a floor area adjacent the pile, comprising:

digging into the side face at its lower end in a path along the 70 length of the side face and creating a first stream of material while digging the angled side face of the pile over an area which extends a substantial distance above the lower end to create a downward flow of material;

confining the downward flow of material to form a second stream of material of a desired width; and elevating the material of the first stream in an arcuate flow about a substantially horizontal axis to a position above the floor area, and then merging the first and second streams of material into a common stream extending angularly away from the side face.

2. A method of reclaiming bulk material from a pile extending along a floor area, the pile having a side face in which the material is reposed at an angle, comprising:

digging into the side face at its lower end in a continuous path along the length of the side face for creating a first stream of material moving in an arcuate flow about a substantially horizontal axis to lift the material above the floor area while digging the angled side face of the pile over an upper area which extends a substantial distance above the lower end for creating a downward flow of material in a continuous path along the length of the upper area; and

confining the downward flow of material to form a second stream of material of a desired width, catching the second stream at a point above the floor area, and directing the first stream and caught second stream angularly away from the side face.

3. A method of reclaiming bulk material from a pile having a side face in which the material is reposed at an angle to a floor area adjacent thereto, comprising:

digging into the side face at its lower end in a continuous path along the length of the side face and creating a first stream of material moving in an upward arcuate path about a substantially horizontal axis to elevate the material above the floor area while digging the angled side face of the pile over an upper area which extends a substantial distance above the lower end to create a downward flow of material in a continuous path along the length of the upper area, confining the downward flow of material to form a second stream of material of a desired width with lateral movement of the second stream being confined by the angled forward wall of the pile being cut away, and directing the first and second streams at a point above the floor area angularly away from the side face.

4. A method of reclaiming bulk material from a pile having a side face in which the material is reposed at an angle to an adjacent floor area, comprising:

digging into the side face at its lower end in a continuous path along the length of the side face and creating a first stream of material moving in an upward arcuate direction about a substantially horizontal axis to lift the material above the floor area, while digging the angled side face of the pile over an upper area which extends a substantial distance above the lower end and creating a downward flow of material in a continuous path along the length of the upper area, confining the downward flow of material to form a second stream of material of a desired width; and

digging into the pile on the pile side of the first stream creating a relatively narrow stream of material and merging it with the first stream of material, and then directing the first and second streams of material at a point above the floor area angularly away from the side face.

5. A method of reclaiming bulk material from a pile having a side face in which the material is reposed at an angle to an adjacent floor area, comprising:

digging into the side face at its lower end in a continuous path along the length of the side face creating a first stream of material;

70 plowing floor area at the base of the pile and causing the plowed material to be merged with the first stream of material;

elevating the material of the first stream above the floor areas in an arcuate path having a substantially horizontal axis; and

digging the angled side face of the pile over an upper area which extends a substantial distance above the lower end and creating a downward flow of material in a continuous path along the length of the upper area, confining the downward flow of material to form a second stream of material of a desired width, and directing the first and second streams of material at a point above the floor areas angularly away from the side face.

6. A method of cutting down a bank having a side face and a floor area in immediate adjacency thereto comprising:

digging into the pile along the side face at a restricted area of the face with respect to the total length of the side face and continuing such digging along the length of the side face;

elevating the thus dug material above the floor in an arcuate flow having a substantially horizontal axis, creating a main stream of material from the thus elevated material flowing above the floor in angular relation away from the side face and discharging the stream above the floor;

cycloidally rotating a series of cutters along the slope of the pile to create a downward stream of flowing material; and catching the downward stream at a point above the floor area and then merging the caught downward stream with the main stream, and creating a dam on the rearward side of the cutters for confining the downward flow of material between the dam and the pile bank to minimize lateral uncontrolled flow of the cut material.

7. A method of reclaiming bulk material from a pile having an angled side face in which the material is reposed at an angle to an adjacent floor area, comprising:

digging into the side face at its lower end in a path along the length of the side face and creating a first stream of

5

material moving in an arcuate path about a substantially horizontal axis to lift the material above the axis while cycloidally digging the angled side face of the pile over an area which extends a substantial distance above the lower end to create a downward flow of material generally at an angle to the first stream of material, confining the downward flow of material to form a second stream of material of a desired width; and

catching the second stream of material at a point spaced above the floor area and redirecting the caught material as a main stream extending angularly away from the side face, and merging the first stream of material into the main stream.

10

8. A method of reclaiming bulk material from a pile having a side face in which the material is disposed at an angle and a floor area intermediately adjacent thereto comprising:

digging into the pile along a lower end of the side face at a restricted area of the face with respect to the total length of the side face and continuing said digging in a direction extending along the length of the side face;

elevating the thus-dug material above the floor in an arcuate stream having an axis extending horizontal to the floor area and substantially perpendicular to the direction of continued digging;

digging the angle side face of the pile in an area which extends a substantial distance above the lower end creating a downward flow of material; and

merging the downward flow of material with the arcuate flow to create a main stream of material flowing angularly away from the side face.
